RELAXATION OSCILLATION GENERATOR

René Barthelemy, Fontenay aux Roses, France,
assignor to Compagnie pour la Fabrication des
Compteurs et Materiel d'Usines a Gaz, Mont-
rouge (Seine), France

Application September 24, 1936, Serial No. 102,263
In France October 4, 1935

10 Claims. (Cl. 250—36)

It is already known to use cold or hot cathode electronic discharge tubes to produce relaxation or "saw-tooth" oscillations such as are used more particularly to produce the movement of the luminous point over the screen in cathode ray oscilloscopes. The conditions to be fulfilled for the production of a good displacement of the beam are the symmetry of the deviation from the position of rest and the linearity as a function of time; these two conditions necessitating in the known systems the use of special tubes and complicated circuits.

The present invention has for its object to solve the same problem by simple means.

15 It consists essentially in disposing the linear elements symmetrically with respect to the relaxation member.

Figure 1 shows an embodiment of the invention, the function of which is explained in Figure 2.

20 Figure 3 shows another embodiment of the invention.

Figure 4 relates to a variation in the method of controlling the relaxation member.

25 As shown in Figure 1, the relaxation element is a gas tube 1 which may function in the known manner. The discharge therein is initiated if the potential of the anode is greater than an upper critical voltage and, once initiated, it only ceases if the potential of the anode falls below a lower critical voltage. The discharge can also be initiated by putting the tube into a conducting condition by the application of a suitable voltage to the grid. It is this latter method which is used. The grid is polarized with respect to the cathode by means of a source 2. The successive discharges are either free or controlled by impulses transmitted, for example, by a transformer 3. The gas tube 1 is inserted between the two circuits 4, 4', each comprising a resistance 5, 5' and a reactance 6, 6' in series, shunted by a condenser 7, 7'. The displacement of the cathode beam is produced by the voltage at the terminals 8 and 9 of the tube 1, whilst the feeding of the quadripole is effected from the terminals 10 and 11. When the tube 1 does not receive any impulse and consequently is not a conductor, the terminals 8 and 10 are at the same potential, and the terminals 9 and 11 are also at the same potential. The condensers 7 and 7' are not charged. The tension between the terminals 8 and 9 is at the maximum. When the tube 1 receives an impulse over the grid, it becomes conductive and the two condensers 55 7 and 7' are immediately charged. The poten-

tial difference between the terminals 8 and 9 decreases in proportion as the condensers are charged and attains rapidly the lower critical voltage v_1 of the tube 1. At this moment the discharge across the tube ceases. By designating with U the voltage applied to terminals 10 and 11 and with u_1 and u_1' , respectively, the voltages attained by the condenser 7 and 7', when the discharge ceases, the following equations can be formed:

$$1 \quad U = u_1 + u_1' + v_1$$

$$2 \quad u_1 = u_1'$$

In order to make the second equation correct, it is necessary that the two circuits 4 and 4' are strictly identical.

When the discharge in the tube 1 ceases, the condensers 7 and 7' are discharged relatively slowly across the resistances and inductances 5, 6 and 5', 6'. If the two circuits 4 and 4' are identical, the two discharge curves of the condensers 7 and 7' are likewise identical. Thus the voltage difference between the terminals 8 and 9 varies from v_1 to U . Assumed that the potential of the terminal 10 is zero and the potential of the terminal 11 is U , the potential u of the terminal 8 will vary from

$$\frac{U - v_1}{2}$$

to zero and the potential u' of the terminal 9 will vary from

$$\frac{U + v_1}{2}$$

35 to U . These two variations are represented in Fig. 2 under the supposition that v_1 be zero. Fig. 2 shows that the variations are symmetrical with respect to

$$\frac{U}{2}$$

40 The linearity of the variations, i. e., of the curves u and u' of Fig. 2 perfectly symmetrical; linearity is obtained due to the use of the reactances 6, 6' according to the method described in my Patent No. 2,105,177 granted January 11, 1938.

45 Another embodiment of the invention is that shown in Figure 3; the symmetry of the displacement is there obtained by inserting the relaxation element 21 in the diagonal of a bridge, the arms of which are, alternately, capacities 21, 21' and resistances 25, 25'. A potentiometer 22 placed in the same diagonal enables the polarization of the grid with respect to the cathode to be varied. When the tube 21 does not re-

ceive any impulse and consequently is no conductor, the terminals 28 and 31 are at the same potential and so are the terminals 30 and 29. The potential difference between the terminals 28 and 29 at this moment equals the feeding potential U . Both the condensers 27 and 27' are charged with the tension U . When an impulse is received over the grid of tube 21, the latter becomes conductive. The condenser 27 is discharged into the resistance 25 and the condenser 27' is discharged into the resistance 25'. These discharges are relatively slow and cease completely, when the potential difference between the terminals 28 and 29 falls below the lower critical voltage v_1 of the tube 21. When the discharges cease the condensers 27 and 27' are recharged immediately to the tension U . It appears, that the potential difference between the terminals 28 and 29 varies slowly from U to v_1 and then increases rapidly from v_1 to U . Also in this case, the voltages of the terminals 28 and 29 are symmetrical with respect to

$$\frac{U}{2}$$

as illustrated in Fig. 2, owing to the symmetrical disposition of the resistances 25 and 25'.

The preceding devices use for the displacement of the beam or scanning the discharge of a condenser, but, according to the present invention, the charge may also be used. Such an arrangement is illustrated in Figure 4 as applied to a modification in which the relaxation element 61 is a high vacuum tube, for example, a triode, having a low internal resistance.

The vacuum tube 61 is connected to the terminals of the relaxation condenser 67, charged by a continuous current through resistances 65 and 73. A potentiometer 62, 71, of high resistance serves to polarise the grid of the tube 61; the positive part 71₁ of this potentiometer is shunted by a gas discharge tube 72 in series with the resistance 76; the operations of 72 are controlled, through the intermediary of the coupling 63, by the synchronizing impulses. Then the condensers 71, 71' are employed to supply the deflecting plates of the cathode tube.

It will be seen that the gas discharge tube 72 plays in this arrangement the part of an on and off relay, each of its operations resulting in the shunting of 71₁, by the resistance 76 thereby rendering the grid of the tube 61 positive. Once the discharge has taken place, the time during which the grid of the tube 61 remains positive can be regulated by the condenser 75 and the resistance 73; the elements 72, 75 and 62 form moreover a relaxation circuit having a relatively long period which assures an operation of the tube 61 at the end of a certain time even in the absence of the synchronising signals.

The invention is so particularly applicable to the known cathode tube scanning systems for television in which the signal synchronising the images consists of the periodic suppression of a line signal. It has moreover the following advantages; use of the gas discharge tube at feeble load whereby a long period of service is secured; a very reduced consumption at high-tension which enables a common feeding source with the cathode tube to be employed.

With a view to assuring the quick extinction of the tube 72 it will be advantageous to connect to its terminals a small capacity 75' (the parasitic capacity of the apparatus may suffice in certain cases).

What I claim is:

1. Device for the production of relaxation oscillations, comprising a discharge tube, at least a cathode, an anode and a control electrode in said discharge tube, means for impressing impulses of voltage to said control electrode, two terminals to be connected to a feeding source, a first circuit comprising a resistance and connected between one of said terminals and the anode of said discharge tube, and a second circuit identical to said first circuit connected between the other terminal and the cathode of said discharge tube, whereby the time variations of the voltage of the said cathode and of the said anode are symmetrical with respect to the mean feeding voltage. 5

2. Device for the production of relaxation oscillations, comprising a discharge tube, at least a cathode, an anode and a control electrode in said discharge tube, means for impressing impulses of voltage to said control electrode, two terminals to be connected to a feeding source, a first circuit connected between one of said terminals and the anode of said discharge tube, a condenser and a resistance in said first circuit, 10 and a second circuit identical to said first circuit connected between the other terminal and the cathode of said discharge tube, whereby the time variations of the voltage of the said cathode and of the said anode, due to the charges and discharges of the condensers in said circuits, 15 are symmetrical with respect to the mean feeding voltage. 20

3. Device for the production of relaxation oscillations, comprising a relaxation element, two first terminals to pick-up the relaxation oscillations and connected to said relaxation element, two second terminals to be connected to a feeding source, a first oscillating circuit connected between one of the first terminals and one of the 25 second terminals, and a second oscillating circuit identical to said first circuit and connected between the two other terminals, whereby the time variations of the voltage of the two first terminals are symmetrical with respect to the mean 40 feeding voltage. 35

4. Device for the production of relaxation oscillations, comprising a discharge tube, at least a cathode an anode and a control electrode in said discharge tube, means for impressing impulses of voltage to said control electrode, two terminals to be connected to a feeding source, a first circuit connected between one of said terminals and the anode of said discharge tube, a resistance and an inductance in series in said 45 first circuit, a condenser connected in parallel with said resistance and inductance in said first circuit, and a second circuit identical to said first circuit connected between the other terminal and the cathode of said discharge tube, whereby the time variations of the voltage of the said cathode and of the said anode, due to the charges and discharges of the condensers in said circuits, 50 are symmetrical with respect to the mean feeding voltage. 55

5. Device for the production of relaxation oscillations, comprising a discharge tube, at least a cathode, an anode and a control electrode in said discharge tube, means for impressing impulses of voltage to said control electrode, two terminals to be connected to a feeding source, a first circuit connected between the positive one of said terminals and the anode of said discharge tube, a resistance in said first circuit, a second circuit identical to said first circuit connected 60 65 70 75

between the negative terminal and the said cathode, a first condenser connected between the anode of the discharge tube and the negative terminal, and a second condenser connected between the cathode of the discharge tube and the positive terminal, whereby the time variations of the voltage of the said cathode and of the said anode, due to the charges and discharges of the said condensers, are symmetrical with respect to the mean feeding voltage.

6. Device for the production of relaxation oscillations, comprising a discharge tube, at least a cathode, an anode and a control electrode in said discharge tube, a condenser connected between said anode and cathode, two terminals to be connected to a feeding source, a first circuit comprising a first resistance connected between said anode and the positive one of the said terminals, a second circuit identical to said first circuit comprising a second resistance and connected between said cathode and the negative one of the said terminals, a second discharge tube, a coupling member receiving the signals and connected to said second discharge tube whereby a discharge is set up in the said second tube by each signal, means for connecting the second tube to said third resistance whereby when a discharge takes place, a part of the third resistance is shunted, whereby the polarization of said control electrode is modified, rendering the first tube conductive and provoking the discharge of the said condenser, the time variations of the voltage of the said cathode and of the said anode being symmetrical with respect to the mean feeding voltage, due to said first and second circuits connection.

7. Device for the production of relaxation oscillations, comprising a discharge tube, at least a cathode, an anode and a control electrode in said discharge tube, a condenser connected between said anode and cathode, two terminals to

be connected to a feeding source, a first circuit comprising a first resistance connected between said anode and the positive one of the said terminals, a second circuit identical to said first circuit comprising a second resistance and connected between said cathode and the negative one of the said terminals, a third resistance connected between the two said terminals, a connection between said control electrode and an intermediate tap on said third resistance for the polarization of the said control electrode, a second discharge tube, a coupling member receiving the signals and connected to said second discharge tube whereby a discharge is set up in the said second tube by each signal, means for connecting the second tube to said third resistance whereby when a discharge takes place, a part of the third resistance is shunted, whereby the polarization of said control electrode is modified, rendering the first tube conductive and provoking the discharge of the said condenser, the time variations of the voltage of the said cathode and of the said anode being symmetrical with respect to the mean feeding voltage, due to said first and second circuits connection.

8. Device according to claim 6 in which the second discharge tube is a gas discharge tube having a control electrode, the said coupling member being inserted in the circuit of the said control electrode of the second discharge tube.

9. Device according to claim 7 in which the second discharge tube is a gas discharge tube having a control electrode, the said coupling member being inserted in the circuit of the said control electrode of the second discharge tube.

10. Device according to claim 7 in which a part of the said third resistance is shunted by a condenser in order to obtain self-sustained oscillations.

RENÉ BARTHELEMY.
